UNITED STATES PATENT OFFICE.

JAMES CARMICHAEL, OF CHICAGO, ILLINOIS.

POURING-SPOUT FOR CANS.

1,299,913.

Specification of Letters Patent.

Patented Apr. 8, 1919.

Application filed July 8, 1918. Serial No. 243,864.

To all whom it may concern:

Be it known that I, JAMES CARMICHAEL, a citizen of the United States, residing at Chicago, in the county of Cook and State of Illinois, have invented certain new and useful Improvements in Pouring-Spouts for Cans, of which the following is a specification.

This invention relates to pouring spouts for use on cans, kegs, and other containers that are designed to hold a liquid which is poured therefrom from time to time into other receptacles or containers. My present invention has been more particularly designed to facilitate the charging of gasolene tanks of motor vehicles from the five gallon cans quite commonly used as storage receptacles for gasolene by automobile owners in their private garages. The common method at present employed necessitates the use of a funnel to facilitate the pouring of the gasolene, as well as a cork or stopper for the nozzle of the gasolene can which must be removed and later re-inserted at each filling operation; and the lifting, inverting and supporting of the heavy can in pouring position; and is at best a laborious, sloppy and more or less wasteful method of transferring the liquid fuel to the fuel holder of the vehicle.

Among the salient objects of the present invention are, to provide an improved pouring device that shall serve both as a sealing plug or stopper for the gasolene can to prevent evaporation or accidental spilling of the contents, and as a means to facilitate the pouring without waste or loss; to provide a pouring device with a normally closed lid or cover which opens automatically as the can is raised to pouring position and supported on the nozzle of the receptacle to be filled, and closes automatically as the can is withdrawn from the nozzle of said receptacle; and to provide an improved means for fastening a detachable pouring device to the nozzle of the can so as to prevent its accidental displacement during the pouring operation.

Other objects and attendant advantages of the invention will be apparent to those familiar with devices of this general character from the following detail description, taken in connection with the accompanying draw-

ing wherein I have shown one practical embodiment of the principle of the invention, 55 and in which—

Figure 1 is a view partly in elevation and partly in vertical section, showing the spout applied to the nozzle of a can, and the lid closed; 60

Fig. 2 is a similar view, showing the device inverted and in pouring position;

Fig. 3 is a horizontal section on the line 3—3 of Fig. 1; and

Fig. 4 is a fragmentary section on the line 65 4—4 of Fig. 1.

Referring to the drawing, 5 designates the body of the spout which may be a straight section of tubing, and the lower end of which is designed to enter the nozzle 6 of a can or other container 7 such, for instance, as the five gallon cans commonly used to hold gasolene and lubricating oils. The nozzle of these cans usually have a bead 8 at their upper ends, and I have herein shown such a 75 beaded nozzle, but my device is capable of use with a plain nozzle. Fast on the body 5, a slight distance above its lower end is an annular flange 9, directly beneath which is an annular gasket or washer 10 of rubber 80 or other compressible material that seats directly on and forms a liquid-tight joint with the bead 8 of the nozzle. In order to detachably secure the spout on the nozzle of the can I provide a releasable clamp which, 85 in the form shown in the drawing, consists of a piece of spring wire bent to provide a pair of curved arms 11 which embrace the nozzle just below the bead 8. These arms 11 are integrally joined at one end by a loop or eye 12 that embraces a pin or stud 13 secured in and depending from the flange 9, and adjacent to their free ends are bent upwardly and passed through a slot 14 in the flange 9, as clearly shown in Fig. 3. The free end of 90 one arm is bent to form a radially extending hook 15, and the free end of the other arm is bent to form a tangentially extending hook 16. In order to draw and fasten the free ends of the arms together, so as to draw the 100 flange and gasket of the spout hard down onto the end of the nozzle and lock the spout in the latter, I employ a piece of curved wire 17 secured by an eye 18 to the base of the hook 15 and engaging with the hooks 16 105 and 15 in the manner clearly shown in Fig.

3. This wire fastener 17 has a free end 17', by grasping which it may readily be placed in and out of engagement with the hook 15 to thereby lock or release the arms 11 of the 5 clamp.

On the outer or delivery end of the spout body 5 is a closure in the form of a lid 19 preferably provided with an internal lining or gasket 20 of compressible material to 10 create a liquid and vapor-proof joint. This lid is hinged at 20 to the body of the spout, and is provided with an arm 21 rigidly attached thereto and extending rearwardly of the hinge 20. Slidably mounted on the body 15 5 is a flange-like disk 22 that, when the spout is in pouring position (Fig. 2), rests on the upper end of the nozzle 23 of the receptacle to be filled, such, for instance, as the gasoline tank of an automobile. This disk is provided with one or more holes 24 that serve to 20 vent the air from the receptacle as it is being filled. Encircling the body 5 is a compression spring 25 which abuts against and is confined endwise between the fixed flange 25 9 and the slidable disk 22 and normally tends to thrust the latter toward the outer or delivery end of the spout. The disk 22 is operatively connected to the lid 19 by a link 26, the lower end of which is looped through 30 a pair of the holes 24, as shown in Figs. 1 and 4, while its upper end hooks through an eye 21' on the outer end of the arm 21 of the lid. On the body 5 is a stop 27 that limits the outward movement of the disk 22 35 to a position in which the lid 19 is tightly closed.

From the foregoing it will be seen that when my improved pouring spout is applied to a can, as shown in Fig. 1, it is 40 strongly secured on the nozzle of the latter in a liquid and vapor-tight manner; and the spring 25, acting through disk 22, link 26, and arm 21, holds the lid 19 tightly pressed on the outer end of the spout. The device 45 may therefore take the place of the ordinary nozzle cap or cork to seal the contents of the can 7 against spilling or evaporation. At the same time it is readily detachable to permit refilling of the can 7 by simply 50 grasping the end 17' of the fastener and swinging it out of engagement with hook 15, the arms 11 then springing apart. In the filling operation, the can 7, with the pouring spout attached thereto, is inverted 55 and the spout is inserted in the nozzle 23 of the receptacle to be filled, in the manner shown in Fig. 2. The weight of the can 7, and its contents compresses the spring 25, thereby automatically opening the lid 19 60 and permitting the contents of the can to flow readily into the receptacle without any leakage or waste. As the can 7 is withdrawn, the lid 19 is automatically closed by the reaction of the spring 25.

65 I have herein shown and described the

device of my present invention as detachable from the can 7, but it is evident that so far as the closure and its automatic actuating mechanism are concerned, it might with equal advantage be made as an integral 70 extension of the can nozzle 6 or other part of the can. Hence, I do not limit the invention to a detachable pouring spout except to the extent indicated in certain of the claims.

75 It is believed that the structure, manner of use, and advantages of the device of the present invention will be clear to those skilled in the art from the foregoing description and the accompanying illustration. 80 It will readily be seen the device combines in itself the functions of the ordinary stopper or cap of the gasoline can and the usual pouring funnel, in addition to the other advantages already described. While I have 85 described the device as one adapted to facilitate the filling of gasoline tanks of motor vehicles from gasoline cans and contemplate that such will be its principal function and use, yet it will be manifest that the invention is capable of general use in any situation where any material capable of being 90 poured is to be transferred from one container to another.

95 It is also evident that the device as shown in the drawing may be modified in details of form and relative arrangement of parts without altering its essential structural and functional characteristics or sacrificing any of the advantages secured thereby. Hence, 100 I do not limit the invention to the exact embodiment herein presented, but reserve all such variations and modifications as fall within the spirit and purview of the appended claims.

105 I claim:

110 1. A pouring spout provided with a hinged lid covering its delivery end, an arm on said lid extending rearwardly of the hinge thereof, a flange-like disk slidably mounted on said spout, a link connecting said disk and said arm, and a spring urging said disk toward the delivery end of said spout.

115 2. A pouring spout provided with a hinged lid covering its delivery end, an arm on said lid extending rearwardly of the hinge thereof, a flange-like disk slidably mounted on said spout, a link connecting said disk and said arm, a coil spring encircling said spout and urging said disk toward the delivery end of said spout, and a stop on said spout co-operating with said disk to limit the extent of outward movement of the latter.

120 125 3. A detachable pouring spout adapted to engage with the nozzle of a can or like container, and having a radial flange adapted to overlie the outer end of the nozzle, and a releasable clamp adapted to embrace the 130

nozzle inwardly of the outer end of the latter and thereby secure said spout on said nozzle.

4. A detachable pouring spout adapted to engage with the nozzle of a can or like container, and having a radial flange adapted to overlie the outer end of the nozzle, an annular gasket below said flange adapted to seat on the outer end of the nozzle, and a releasable clamp adapted to embrace the nozzle inwardly of the outer end of the latter, thereby securing a liquid-tight engagement of said spout with said nozzle.

5. A detachable pouring spout adapted to engage with the nozzle of a can or like container, and having a radial flange adapted to overlie the outer end of the nozzle, an annular gasket below said flange adapted to

seat on the outer end of the nozzle, and a releasable clamp comprising a pair of curved arms anchored to said flange and adapted to embrace the nozzle inwardly of the outer end of the latter.

6. A detachable pouring spout adapted for engagement with the beaded nozzle of a can or like container, and having a radial flange adapted to overlie the outer end of the nozzle, an annular gasket below said flange adapted to seat on the bead of the nozzle, a releasable clamp comprising a pair of curved arms anchored at one end to said flange and adapted to embrace the nozzle below the bead thereof, and means for drawing together the free ends of said arms to clamp them on said nozzle.

JAMES CARMICHAEL.
